ANTENNA

Ernest O. Johnson, Haddonfield, N.J., assignor to Radio Corporation of America, a corporation of Delaware

Continuation of design applications Ser. No. 361 and Ser. No. 368, Dec. 29, 1965. This application Oct. 21, 1966, Ser. No. 5,365

Term of patent 14 years

(Cl. D26—14)

FIG. 2.

Fig. 4.

Fig. 5.

Fig. 7.

Fig. 6.

Fig. 8.

FIG. 1 is a right side elevational view of an antenna, showing one form of my new design wherein there are provided 11 reflector rods, the left side being substantially a mirror image thereof;

FIG. 2 is a front elevational view of the form shown in FIG. 1;

FIG. 3 is a top plan view of the form shown in FIG. 1, the bottom being substantially a mirror image thereof;

FIG. 4 is a rear elevational view of the form shown in FIG. 1;

FIG. 5 is a right side elevational view of an antenna, showing a second form of my new design wherein there are provided 15 reflector rods, the left side being substantially a mirror image thereof;

FIG. 6 is a front elevational view of the form shown in FIG. 5;

FIG. 7 is a top plan view of the form shown in FIG. 5, the bottom being substantially a mirror image thereof; and

FIG. 8 is a rear elevational view of the form shown in FIG. 5.

This application is a continuation of my copending applications Nos. D. 368 and D. 361, both filed Dec. 29, 1965, and both abandoned subsequent to the filing of this application. The free ends of the V-shaped support for the round reflector rods are covered by plastic caps and are so shown in the drawing.

I claim:

The ornamental design for an antenna, substantially as shown and described.
